UNITED STATES PATENT OFFICE

2,553,240

STONE PICKING MACHINE

Alois Louis Cintula, Norwood, Mo.

Application July 30, 1948, Serial No. 41,525

1 Claim. (Cl. 55—17)

1

This invention relates to a stone picking machine.

It is an object of the present invention to provide a stone picking machine adapted to be connected to a tractor or the like and to have its operating depth gauged from the tractor hitch bar and operable by a lever on the machine and accessible from the operator's station on the tractor and wherein the stone receiver is so located at the rear of the frame that the stones can be dumped without other parts of the machine interfering with the operation and wherein the pull cord for releasing the stone receiver door extends forwardly along the machine and is accessible to the operator on the tractor.

Other objects of the present invention are to provide a stone picking machine of the trail behind type which has its own power plant for driving the pickup device and the conveyor for elevating the stone to the stone receiver and depth adjusting mechanism, which is of simple construction, easy to attach to the tractor, easy to adjust, has minimum and durable parts, inexpensive to manufacture, and efficient in operation.

For other objects and for a better understanding of the invention, reference may be had to the following detailed description taken in connection with the accompanying drawing, in which:

Fig. 1 is a top plan view of the stone picking machine embodying the features of the present invention.

Fig. 2 is a side elevational view of the machine.

Fig. 3 is a side elevational view of the machine as viewed from the opposite side from which the machine is viewed in Fig. 2.

Fig. 4 is a transverse sectional view taken generally on line 4—4 of Fig. 2.

Fig. 5 is a transverse sectional view taken generally on line 5—5 of Fig. 2.

Fig. 6 is a rear elevational view of the machine.

Fig. 7 is a bottom plan view of the receiver and of the latch mechanism for retaining the receiver door in its closed position while being filled with stones, the view being taken generally on line 7—7 of Fig. 6.

Fig. 8 is a transverse sectional view taken on line 8—8 of Fig. 2.

Fig. 9 is an enlarged sectional view taken generally on line 9—9 of Fig. 8 and through one of the digging teeth and showing the manner in which each tooth is connected to the transverse support bar.

Fig. 10 is an enlarged sectional view taken through the conveyor mechanism and on line 10—10 of Fig. 2.

2

Fig. 11 is a detail elevational view of one of the spacing rollers for the conveyor.

Fig. 12 is a detail sectional view taken on line 12—12 of Fig. 1.

Referring now to the figures, 15 represents a frame comprising side members or portions 16 of channel section. These side members respectively have bearings 17 in which is journaled a straight axle 18 having respectively rubber tired wheels 19. On the front of the frame is a platform 21 on which is mounted power plant 22. This power plant has a drive pulley 23 connected through a belt 24 with a large pulley 25 on a shaft 26 journalled in bearings 27, 28 and 29, 15 transversely aligned on the platform 21.

Pivotedly connected to the forward end of the frame 15 as at 31 is a hitch bar 32 adapted to be connected to the draw bar of a tractor by a hitch pin 33 thereof. To the lower end of the 20 bar 32 there is connected a link 34 depending from an arm 35 of an adjustable lever 36 pivoted to the frame at 37 and operable over a quadrant 38. The lever has a detent device 39 engageable with the quadrant to hold the lever in its adjusted position. Movement of the lever will adjust the forward end of the frame, the hitch bar of the tractor being disposed in a fixed vertical position.

Connected between the sides of the frame and 30 depending from the bottom of the same is a transverse support bar 41 to which are connected a plurality of diggers or teeth 42. These teeth are made secure by U-clamps 43 vertically spaced from one another and extending through the bar 41, Figs. 8 and 9, and made secure to the bar by nuts 44. These teeth will loosen the ground and the stones therefrom. The depth of operation of these teeth is controlled by the position of the draw bar 32. The handle 36 extends toward the tractor and is accessible to the operator's station.

Depending from the opposite sides of the frame are brackets 45 having a rotary pick-up device or mechanism 46 journaled thereacross. This 45 pickup device lies in rear of the teeth 42 and will pickup the loosened stone and fling the same onto a conveyor mechanism 47. The pickup device 46 has rows of teeth 48 and a pulley 49 which is connected by a belt 51 with a pulley 52 on a gear 53 meshed with a gear 54 of shaft 26 driven by the power plant 22.

The shaft 26 has a pulley 55 connected by a belt 56 with a pulley 57 of a drive shaft 58 of the conveyor mechanism 47. The conveyor 55 mechanism has a traveling belt 59 which extends over the drive shaft 58 and is supported

in an elevated position on a roller 61 journalled on the upper end of conveyor frame pieces 62. The lower end of the conveyor frame pieces have an apron 63 which extends beneath the pickup device 46 to receive the stone therefrom.

An adjustable idler pulley device 64 is connected to each side of the conveyor frame and has a roller sprocket 65 engageable with the under side of the conveyor chain 59. This device 64 is adjustable on the side frame, Figs. 11 and 12 and will retain the conveyor belt on its under side against upward displacement and against entanglement with the upper side thereof. The side frame pieces 62 of the conveyor mechanism are supported near their upper ends by braces 68 and at their lower ends by depending braces 69.

Between the side frame members and at the rear thereof there is fixed a stone receiver 71 of hopper shape and with a curved bottom 72. A door 73 is hinged at its upper edge at 74 and may be lifted from its bottom edge when released upon the stone being discharged from the receiver. The door 73 will return by gravity and will be retained in its lowered position by a hook latch 75, Fig. 7, journalled in bearings 76 on the bottom of the hopper and having a spring 77 urging the same to a closed position. An arm 78 depends from the latch and is connected by a pull cord 79 to a forwardly and upwardly extending bracket 81 on the front of the frame where the pull cord will be accessible to the operator on the tractor. It will be apparent that when this pull cord is pulled, that the door will be released and the stone will be discharged. Door 73 will return to its closed position by gravity and past the latch 75.

On the support 81 is an adjustable lever 83 which is connected by a wire 84 to the power plants to control the speed of operation of the same. This wire 84 is connected with an arm 85 with a pulley 86 thereon. The pulley will engage the belt 24 to control the slippage of the belt 24 on the power plant pulley 23. The adjusting lever 83 is easily accessible to the operator on the tractor and can be fixed at any position on quadrant 87.

It should be apparent that there has been provided a stone picking machine which can be directly connected to a tractor in such a manner

that the depth of operation of the digger is gauged from the tractor and wherein the stone when picked up will be elevated and delivered to a stone receiver. When the stone receiver has been filled, the rear door can be released and the stone discharged. If it is desired to haul the stone from the field, the forward end of the frame will be elevated to a position on the tractor whereby the teeth 42 will be withdrawn from the ground.

While various changes may be made in the detail construction, it shall be understood that such changes shall be within the spirit and scope of the present invention as defined by the appended claims.

I claim:

In a stone picking machine, a mobile frame including a pair of spaced parallel side portions, a platform arranged on the front of said frame, 20 and a power plant supported on said platform, of a bracket dependently carried by each of said side portions, a horizontally disposed shaft supported above said platform and driven by said power plant, a rotary pickup mechanism connected to said brackets and including a plurality of teeth, belt and pulley means connecting said pickup mechanism to said shaft, an inclined conveyor mechanism having its rear end arranged adjacent to said pickup mechanism, belt and pulley means connecting said conveyor mechanism to said shaft, and an apron projecting from said conveyor mechanism and extending beneath said pickup mechanism.

ALOIS LOUIS CINTULA.
